UNITED STATES PATENT OFFICE

DE WITT FOX, OF NEW YORK, N. Y.

DESIGN FOR A SUSPENDERS

Application filed April 9, 1932. Serial No. 43,442. Term of patent 7 years.

To all whom it may concern:

Be it known that I, DE WITT FOX, a citizen of the United States, residing in the city, county, and State of New York, have invented a new, original, and ornamental Design for Suspenders, of which the following is a specification, reference being had to the accompanying drawing, forming part thereof, in which the figure is a plan view of a suspender, showing my new design.

The design comprises a back strap of wire spring construction formed with coils along each of its sides and having a cord laced vertically through the middle portion of the spring.

What I claim is:—

The ornamental design for a suspender substantially as shown and described.

DE WITT FOX.
